UNITED STATES PATENT OFFICE.

GEORGE N. BLANCHARD, OF SAN FRANCISCO, CALIFORNIA, ASSIGNOR TO COLMAR BURNER CO., OF SAN FRANCISCO, CALIFORNIA, A CORPORATION OF CALIFORNIA.

FURNACE.

Application filed November 27, 1922. Serial No. 603,516.

To all whom it may concern:

Be it known that I, GEORGE N. BLANCHARD, a citizen of the United States, residing at city and county of San Francisco and 5 State of California, have invented certain new and useful Improvements in Furnaces, of which the following is a specification.

This invention relates particularly to an apparatus for supplying heated air for 10 warming residences or store buildings or for commercial purposes.

It has been considerable of a problem to provide a heat generating apparatus that would operate efficiently and uniformly under 15 greatly varying conditions.

On account of the ready availability of fuel oils and gas it has been the effort to utilize these fuels in heating apparatus designed for residence and commercial heating, but certain difficulties have been 20 encountered that have heretofore made these fuels somewhat impractical and hazardous unless full automatic equipment was employed, and even with such equipment certain 25 conditions of operation of the heating plant was brought about that still caused trouble at times.

One of the principal difficulties has been the overheating of the burner in heating 30 apparatus of the ordinary type.

A principal object of this invention resides in so constructing an air heating device that an internal circulation of air is created and maintained around the burner 35 elements in such a manner that the burner under maximum operation remains comparatively cool and continues to function satisfactorily and without interruption, for long periods of time, under greatly varying 40 demands.

Another object of the invention lies in so designing an apparatus for the heating of circulating air that the maximum heat is imparted to the air through a specially arranged system of heat conducting chambers, whereby the heat generated from the oil or 45 gas burners is conveyed through a circulatory path and in contact with a large wall area of heat conducting material, which permits the outer circulating air to absorb the bulk 50 of the heat accumulated by the large wall area and thus assist materially in keeping the burners in a comparatively cool condition.

55 Another object of the invention resides in

producing a design of air heating apparatus that will be of light weight to minimize transportation costs and of a type of material that will offer the minimum resistance to the transfer of the heat units and thereby 60 effect a maximum rapidity of heat transmission in the operation of the apparatus.

With such object in view, as well as other advantages which may be incident to the use of the improvements, the invention consists in the procedure, and in the parts and combinations thereof hereinafter set forth and claimed, with the understanding that the several necessary elements constituting the same may be varied in proportions and 65 arrangement without departing from the nature of the invention.

In order to make the invention more clearly understood there are shown in the accompanying drawings means for carrying 75 the same into practical effect, without limiting the improvements in their useful applications, to the particular constructions which, for the purpose of explanation have been made the subject of illustration. 80

Figure 1 of the drawings illustrates a front view of an apparatus embodying my invention and with certain portions of the structure broken away to better illustrate the interior and adjacent parts. 85

Figure 2 is a sectional plan taken on line 2—2 of Fig. 1, looking in the direction of the arrow and illustrates the general arrangement of the interior of the apparatus, a burner being shown in outline by dotted 90 lines.

Figure 3 is a side elevation looking in the direction of the arrow 3 of Fig. 1, with portions of the apparatus broken away to show the general arrangement of the interior construction. 95

Fig. 4 is a perspective of a portion of the heating apparatus on a somewhat larger scale and with portions broken away to better show the extent of the heating area and 100 to better illustrate the heat and air circulation.

In the development of a heater of the high efficiency we have obtained it has been the aim to produce a construction that would 105 create a circulation of the heat currents from the burner, in such a manner that as the hotter portions of the heat currents ascended they would encounter wall area of such a large extent and arrangement as would 110

rapidly accumulate the heat units and cause the heat currents to be deflected downward in their course and flow back toward the base of the heat compartment and there combine with the incoming air necessary to maintain combustion, and thereby assist in keeping the burner elements cool enough to operate continuously under varying demands and in a highly satisfactory manner.

10 In arranging a wall area of sufficient extent to accumulate the heat units fast enough to attain the desired cooling effect at the burner, it was also necessary to provide an equal wall area in the air circulating compartment, so that the air passing through the apparatus would absorb the heat accumulated by the extended walls as fast as it was taken up from the heat compartment by the walls.

20 The arrangement of elements, and their combinations to effect the above enumerated results has been brought about after exhaustive experiments and tests in the following manner.

25 In the drawings the invention has been illustrated as applied to a residence or store heating apparatus.

The numeral 1 represents a casing or jacket surrounding the heating apparatus 30 on all sides. The front of the casing carries a door frame 2 in which is mounted a door 3 and an air inlet 4, all of ordinary construction. At the rear of the casing 1 is an ordinary flue or smoke pipe 5.

35 To obtain a maximum wall area for quickly accumulating the heat units and one in which a multiplicity of heat circulating chambers would be available I have built up a square unit having opposed sides composed 40 of a series of U-shaped elements connected in reverse order, thus producing a series of zig-zag, alternating chambers, lying side by side in parallel relation, part of which form chambers opening into the burner and heat 45 circulating compartment and the others forming chambers through which the air coming into, and passing out of the apparatus, will circulate.

The arrangement of the heat accumulating 50 walls is shown in plan in Fig. 2, side elevation in Fig. 3 and in perspective in Fig. 4, the latter figure giving a much better idea of the arrangement and may be particularly referred to in reading the following description.

55 The heat accumulating walls are preferably made of some thin sheet material such as galvanized iron, and either bent into shape or cut into sheets of proper size and extent and their contiguous edges welded or otherwise secured together.

60 The U sections are preferably made with square corners. The sections forming the chambers opening into the burner and heat circulating compartment 6 are designated

by the numeral 7, and the adjacent chambers through which the circulating air passes in going through the apparatus are designated by the numeral 8. Arrows are used liberally to indicate the directions of flow of the currents set up in the heat compartment, and the direction of flow of air passing through the apparatus.

70 The heating element as a whole is composed of the walls 9 forming the chambers 7 and 8. All of the chambers 7 are closed top and bottom by walls 10 and 11.

75 A compartment 12 is provided to contain the burner, this compartment forming a box closure for the bottom of the heat compartment.

80 The top of the heat compartment is closed by a continuation of the walls 10 connecting the opposite chamber sections.

85 This wall construction completely encloses the heat compartment and prevents any leakage of products of combustion into the air heating and circulating compartments 8.

90 At the rear of the apparatus is a wall 13 covering all of the rear heat compartment space except a small elongated opening 14 at the top, through which the products of combustion pass into a chamber 15 having a partition 16 just below the smoke pipe 5.

95 The operation of the apparatus is as follows:

The heat from the burner rises to the top of the compartment and, coming into contact with the wall 10 is spread and deflected, some passing laterally into the chambers 7. 100 The walls 9 being cool, quickly accumulate heat units, thus cooling the heat currents and causing them to move downward in the chambers, as is indicated by arrows in Fig. 4. As the heat currents move downward, more heat units are given up to the walls 9, until by the time they reach the bottom of the chambers 7 they are quite cool compared to the temperature they had when entering into the tops of the chambers 7.

105 This downward movement of the heat laden currents in the chambers 7 is also assisted by the increasing pressure of added heat laden currents crowding into the top of the heat compartment and spreading out 110 into the tops of the chambers.

115 As long as a fire is burning in the heat compartment a circulation of heat currents is maintained in the manner described and becomes quite rapid so that a partial vacuum 120 is created in the bottoms of the chambers 7 which also assists in creating the circulation described.

125 The air for maintaining combustion enters the opening 4 in the front of the apparatus, located under the fire door.

130 The burner 18 is only shown in dotted outline in the figures as it is no part of this invention it was not thought necessary to show it in more detail.

The air to be heated enters the apparatus through the air pipe 19 and spreads according to the speed of the circulation through the circulating chambers 8, absorbing 5 the accumulated heat from the wall areas 9 and thus becomes heated as it moves upward and emerges through the pipes 20, from whence it is conveyed to such portions of the building as may be desired.

10 The manner in which an oil or gas burner in this apparatus is maintained in a comparatively cool condition to what takes place in an ordinary heating apparatus, is very marked.

15 The walls separating the heat compartment from the air circulating compartment, being very thin, accumulate and transmit heat units from the heat currents circulating through the pocketed chambers forming the 20 two sides of the heat compartment, very rapidly and the air currents circulating around the other sides of these thin walled chambers absorb the heat equally as rapidly and thus the heat currents are cooled in the heat compartment to an extent that causes a rapid 25 drop in their temperature and a consequent rapid downward movement in the accumulating chambers that immediately sets up a circulation from top to bottom of these 30 chambers which moves the column of air in each chamber out into the vicinity of the burner where it combines with the incoming air that supports combustion and thus aids very materially in keeping the burner 35 elements cool so that they may function satisfactorily without unnecessary attention.

Furthermore, this forced circulation of the heat currents within the chambers forming a part of the heat compartment and 40 causing them to absorb and deliver heat units to the accumulating walls in such rapid sequence aids materially in reducing the quantity of fuel necessary to maintain the desired temperature of the circulating air 45 outside and around the heat compartment, because, while the heat currents give up a large part of their heat units to the accumulating walls, they do not surrender all 50 of the heat, and return to the burner vicinity at a much higher temperature than the

incoming air needed to support combustion, and since these heated currents are in a measure, used over and over, due to their circulation less outside cool air is needed to support combustion, with the result that 55 less fuel is needed to keep the heat currents at the desired temperature to supply the demand.

Having thus described my invention, what I claim as new and desire to secure by 60 Letters Patent is:

1. An apparatus for heating purposes comprising a suitable source of heat supply, a heat compartment within the base of which said supply is located, said compartment 65 being composed of a series of heat accumulating units arranged in parallel relation and having openings communicating with the upper and lower areas of said compartment and through which heat currents rising in said compartment may enter and circulate and return to said heat compartment in the zone of said heat supply, an air compartment surrounding said heat compartment and through which air circulates and 70 becomes heated from contact with the walls of said heat compartment.

2. An apparatus for heating purposes comprising a heat compartment, a source of heat supply located near the bottom of the heat compartment, said heat compartment having end, top and bottom closures, the side walls of said compartment being formed of a zigzag construction producing pocketed 80 chambers lying in parallel relation and having openings facing said heat supply, said openings extending for the full height of said heat compartment, the side walls of said pocketed chambers forming spaces 85 through which air may circulate and become heated during its passage therethrough, one of said heat compartment walls being provided with an opening for admitting air to sustain combustion and another wall provided with an opening for permitting the 90 outward passage of the products of combustion.

In testimony whereof I have signed my name to this specification.

GEORGE N. BLANCHARD.
